(57) **CLAIM**

The ornamental design for an inflatable doorframe helmet, as shown and described.

DESCRIPTION

FIG. 1 is a perspective view of the inflatable doorframe helmet of the present invention;

FIG. 2 is another perspective view of the inflatable doorframe helmet of FIG. 1;

FIG. 3 is a bottom view of the inflatable doorframe helmet of FIG. 1;

FIG. 4 is a top view of the inflatable doorframe helmet of FIG. 1;

FIG. 5 is a right side view of the inflatable doorframe helmet of FIG. 1;

FIG. 6 is a left side view of the inflatable doorframe helmet of FIG. 1;

FIG. 7 is a front view of the inflatable doorframe helmet of FIG. 1; and,

FIG. 8 is a back view of the inflatable doorframe helmet of FIG. 1.
